COAT HANGER

Roger M. Snook, San Francisco, Calif., assignor of one-half to Henry Gifford Hardy, Berkeley, Calif.

Application August 2, 1954, Serial No. 31,712

Term of patent 14 years

(Cl. D80—8)

The characteristic feature of my design resides in the combination hook and handle portion as shown.

I claim:

The ornamental design for a coat hanger, as shown and described.
